UNITED STATES PATENT OFFICE.

FRANK FOREMAN, OF TORONTO, ONTARIO, CANADA.

BENDING MACHINE.

Application filed September 8, 1925. Serial No. 55,122.

The principal objects of the invention are, to provide a machine which will greatly reduce the cost of bending bars, tubes and rods or angle and channel-bars to curved shapes, and to enable the bending of various sizes and cross sectional shapes with the minimum amount of labor and change of parts.

A still further object is to enable the formation of special cross sectional shapes by reforming of standard sections.

The principal feature of the invention consists in the novel construction and arrangement of parts, whereby adjustable vertical rolls are driven from a transverse threaded shaft and a third roll is supported upon an adjustable carriage.

A further important feature consists in the novel adaptation of the machine to operate flanging rolls or shaping or reforming bars of various designs.

In the drawings, Figure 1 is a plan view of the machine.

Figure 2 is a front elevational view.

Figure 3 is a side elevational view.

Figure 4 is an enlarged mid-sectional view through the carriage shifting member taken on the line 4—4 of Figure 1.

Figure 5 is an end elevational detail of the hub and gear structure of the carriage shifting member shown in Figure 4.

Figure 6 is an enlarged plan detail showing an attachment arrangement for reforming metal sections.

Figure 7 is a vertical sectional view on the line 7—7 of Figure 6.

Figure 8 is an elevational part sectional detail of a rod or tube bending roll.

Figure 9 is a part elevation and part sectional detail showing a roller construction for handling channel-bars.

Figure 10 is a detail similar to Figure 9 showing a structure for handling angle bars.

In the construction of the machine herein shown, the base 1 is formed with an upright portion 2 at one end and said upright is provided with laterally extending flanged sections 3 forming horizontal guideways 4 on which are mounted the flanged carriages 5. These carriages are each provided with vertical cylindrical bearing members 6 in which are mounted the roller spindles 7.

Each of the roller spindles is provided at its lower end with a worm wheel 8 which meshes with a transversely arranged horizontal threaded spindle 9 supported in the

bearings 10 extending upwardly from the base.

A suitable adjusting spindle 11 is journalled at the ends of the guides 4 and is provided with right and left hand threads 60 to operate both carriages to move outwardly or inwardly simultaneously.

The worm wheels 8 remain constantly in mesh with the spindle 9 and upon the rotation of the spindle 9 the vertical roller spindles are revolved.

The roller spindles are provided with flanged and longitudinally keyed upper ends 12 on which suitable rollers to handle the work may be placed.

The spindle 9 is provided with a bevelled gear 13 at one end and a shaft 14 arranged in brackets 15 is provided with a bevelled gear 16 to mesh with the bevelled gear 13 and a bevelled gear 17 at the other end meshing with a bevelled gear 18 on a shaft 19, which is journalled in a frame extension 70 from the base.

The shaft 19 is driven through a suitable arrangement of change gear mechanism, the details of which it is not necessary to here describe, as they are of a very common construction.

A reverse clutch 21 is arranged on the jack shaft 22 of the change gear mechanism and 85 is operated by a lever 23.

The change gear mechanism is operated by a shift bar 24 slidably arranged in suitable guides on the frame so that the operator may manipulate the clutch and the 90 change gear from the same side of the machine.

An extension 25 from the base 1 is formed with a guideway 26 at the top, upon which is mounted a carriage 27 to slide transversely of the plane of movement of the carriages 5. On this carriage is mounted a vertical roller spindle 28.

The carriage 27 is operated to move on its guideway 26 by a threaded stationary 100 spindle 29 (Fig. 4) secured thereto and extending into a threaded tubular nut 30, which nut is preferably supported at its outward end by a ball thrust bearing 31.

A hand wheel 32 is secured to the outer 105 end of the tubular member 30 for rotating the nut.

A bevelled gear 33 is secured to the tubular member 30 inside the hand wheel and is engaged by a pinion 34 on a shaft 35 ex- 110

tending angularly downward from the adjusting member and said shaft is operated by a bevelled gear shaft 36 horizontally journalled in brackets on the base of the frame.

5 The latter shaft is in turn operated by a bevelled geared vertical shaft 37 which meshes with a bevelled gear spindle 38 on which is mounted the hand wheel 39.

The hand wheel 39 is arranged adjacent 10 to the control lever 23 and the handle of the gear shift 24 so that the carriage may be manipulated from a portion adjacent to the other controls.

It will be understood that many different 15 forms of rolls may be devised for use with a machine of this kind, one form of roll being shown in Figure 8, the perimeter of which is divided into a number of varying sized grooves to receive pipes or rods of different diameters.

When rods or pipes are to be bent the 20 rolls are placed on the three vertical spindles and the spindle 11 is manipulated to move the two outer spindles to the desired position apart, according to the bend that is to be given to the rod.

The rod is inserted between the two laterally adjustable spindles and the intermediate vertical spindle 28 is operated through the 25 direct hand wheel or the indirect hand wheel mechanism to tighten against the opposite side of said rod. The clutch is then manipulated to rotate the main driving spindle 9. This rotates the two vertical spindles carried 30 in the carriages 5 and the rollers feed the rod through, imparting a bending stress according to the pressure applied to the centre roll and according to the pressure applied by the driving rolls through the manipulating 35 spindle 11.

It will be understood that by reason of the various adjustments of the spindles any desired radius of arc may be given to a bar or pipe. Special rolls are provided when 40 special sectional forms are to be bent. In Figure 9, for instance, the centre roll 40 is a plain cylinder to fit against the outer side of the web of a channel-iron section 41, while the driving rolls 42 are shaped to fit 45 between flanges. The rolls 42 may be used with the roll 40 in the bending of angle-bars by having their flat faces spaced apart by a spacing disc 43.

It will also be understood from this 50 description that a machine constructed as described may be adapted for the bending of almost any form of bar or tube and any desirable bend may be given to it, either short or long or reverse bends.

55 The machine is also adaptable for use in the reforming of metal sections, such for instance, as angle bars. If it is desired to reform an angle bar into a bar of a very sharp V-shaped section or a similar deformation of the flanges of an angle bar, or

a channel, are desired, a supplementary carriage 44 (see Figure 6) is placed upon the guideway 26.

The carriage 44 supports a pair of vertical spindles 45 upon which are mounted 70 suitable flanged rollers 46 to correspond with the desired flanged rollers 47 on the driven spindles 7.

The vertical spindles 45 are fixed in the carriage 44 and are provided with T-shaped 75 heads 48 in which are rigidly mounted the horizontal spindles 49.

The spindles 49 have mounted thereon the bevelled gears 50 which mesh with bevelled gears 51 carried by the rollers 46 and 47 80 and a deforming roller 52 is provided also on the spindle 49 to extend between the perimeters of the rollers 46 and 47.

Bottom rollers 53 are secured on the spindles on the face of the carriage 44 if 85 desired, to support the bottom edge of the bar being deformed.

A bracket 54 extends laterally from one side of the carriage and supports a guide roller 55 which leads the bars to be deformed 90 into engagement with the deforming rollers.

Straightening rolls 56 and 57 are supported on a rigid bracket 58 arranged at the opposite side of the carriage.

This structure enables the device to be 95 used in straightening or reforming metal bars.

What I claim as my invention is:—

1. A bending machine comprising a base, an upright extending above one end of said base, flanges on said upright extending horizontally and forming guidways, a pair of carriages mounted on said guidways, means for moving the carriages in unison toward or away from each other along said guidways, a guideway arranged above the base in transverse relation to said flanged guidway and terminating short thereof, a carriage mounted on said transverse guideway, roller spindles journalled in said carriages, means for driving said roller spindles, and means mounted in said upright for moving said latter carriage on its guideway.

2. In a bending machine, a frame, a guideway extending transversely of said frame at one end thereof, a pair of carriages on said guideway, means for moving said carriages in unison in opposite directions along said guideway, a guideway extending longitudinally of the frame and disposed intermediate of the length of said transverse guideway, a carriage mounted on said longitudinal guideway, roller spindles mounted in said carriages adapted to receive rolls, a fixed bearing on the frame, a rotatable nut mounted in said fixed bearing, a threaded spindle rigidly fixed to said longitudinally slidable carriage and engaging said nut, and means for rotating said nut.

3. A machine, comprising, a frame, a

threaded horizontal shaft journalled in the frame, carriages adjustably carried by the frame, a pair of vertical roller spindles journalled in the carriages, worm wheels on said 5 spindles meshing with said shaft, rolls mounted on the upper ends of said spindles, spindles mounted parallel with the aforesaid spindles, rolls mounted on the latter spindles and in the same horizontal plane as said 10 former rolls, and means for driving the latter rolls from the former rolls.

4. A machine, comprising, a frame, a threaded horizontal shaft journalled in the frame, carriages mounted on the frame and 15 adjustable longitudinally of said shaft, a pair of vertical roller spindles journalled in said carriages, worm wheels on said spindles meshing with said shaft, rolls mounted on the upper ends of said spindles, spindles 20 mounted parallel with the aforesaid spindles, rolls mounted on the latter spindles and in the same horizontal plane as said former 25

rolls, bevel gears arranged on each of said rolls, spindles mounted horizontally between said roll spindles, and bevel pinions on said 25 latter spindles meshing with said bevel gears.

5. A machine, comprising, a frame, a threaded horizontal shaft journalled in the frame carriages mounted on the frame and 30 adjustable longitudinally of said shaft, a pair of vertical roller spindles journalled in said carriages, worm wheels on said spindles meshing with said shaft, rolls mounted on the upper ends of said spindles, spindles mounted parallel with the aforesaid spindles, rolls 35 mounted on the latter spindles and in the same horizontal plane as said former rolls, bevel gears arranged on each of said rolls, spindles mounted horizontally between said roll spindles, bevel pinions on said latter 40 spindles meshing with said bevel gears, and rolls mounted on said horizontal spindles between the aforesaid rolls.

FRANK FOREMAN.
